UNITED STATES PATENT OFFICE.

RICHARD M. VAN VALKENBURGH, OF KANSAS CITY, MISSOURI, ASSIGNOR TO IRVING-PITT MANUFACTURING COMPANY, OF KANSAS CITY, MISSOURI, A CORPORATION OF MISSOURI.

VISIBLE-INDEX DEVICE.

Application filed June 28, 1926. Serial No. 119,226.

This invention relates to a visible index device and has for its primary object the provision of certain improvements in means for cooperating with a plurality of sheet-holding elements to hold a number of sheets or cards in the proper position after they have been inserted or positioned on the holding members.

One of the primary objects of the instant invention is the provision of a novelly constructed leaf adapted to preclude objectionable displacement of one, or all of the sheets which are positioned thereon in overlapping relation.

Still another object of the invention is to provide a novel structure which will permit of removing or placing any of the visible index sheets without interference, yet will perform the proper holding function at all times.

Yet a further object of this invention is the provision of coacting sheets and holding means which will assure a firm grip along the bound edge.

Many minor objects will appear during the course of the specification referring to the accompanying drawings, in which:

Figure 1 is a plan view of a loose-leaf book adapted to hold a large number of sheets in overlapped relation showing a supporting leaf therein made in accordance with my invention.

Fig. 2 is a fragmentary vertical section of the device showing a sheet in place ready to be positioned beneath the gripping bar.

Fig. 3 is a similar section showing the gripping bar partly raised.

Fig. 4 is a like section showing the relation of parts when a sheet is being removed.

Fig. 5 is a similar section with the gripping bar raised to release its hold on the sheet being removed.

Fig. 6 is a perspective view of the supporting leaf made in accordance with this invention.

Fig. 7 is an enlarged fragmentary cross-sectional view through a means for locking the gripping bar in the open position.

Fig. 8 is a plan view of a modified form of supporting leaf showing the same in a ring binder, and,

Fig. 9 is a vertical cross-section of the modified form of leaf entirely removed from the binder.

Like reference characters refer to like

parts throughout the several views, and Figs. 1 to 7 inclusive illustrate a preferred way of making a leaf in accordance with the invention. It is understood that many structural changes may be made, all of which will conform to the present invention and that the well-known ring binder 9, which has here been shown as the means for supporting the many sheets 10 in the proper overlapped relation, may be any suitable device.

As is customary, the binder is made up of coacting prongs 12, which open and close in the well-known manner. Leaf 13, which carries the important structural features of the invention, should be made of extra heavy material to hold the overlapping sheets 10 flat while entries are being made thereon. The backs of the many sheets 10 may be written upon after they are carried over prongs 12 to lie against the back of the adjoining leaf 13. Thus, a perfect writing surface is presented for both sides of sheets 10 without removing them from position in the holder.

In the preferred form, leaf 13 carries a reinforcing strip 14 adjacent the bound edge and has perforations 15 extending therethrough spaced apart to conform to the distance between the binder prongs 12. A sheet-gripping member 16 may be supported by reinforcing strip 14 in such a manner that it will be movable into a position against all of the sheets 10 when they are in the bound position. In the instance shown, gripping member 16 is hingedly mounted as 17 to edge of strip 14 and is provided with springs or analogous resilient means 18 which will always urge the gripping member to the closed or sheet-engaging position shown in Figs. 1 and 2. The structure shown herein provides for a plurality of these springs 18, each of which is wound about the hinge pin 17 in the well-known manner. The free end of gripping member 16 should be curled slightly as at 19 to assure effective pressure against all sheets 10. Notches 20 are provided along the free edge of gripping member 16 which straddle the respective adjacent prong 12 to allow free movement of member 16 when the prongs are in either the open or closed position.

It may be desired to lock member 16 in the open position as sheets 10 are being positioned. This position is clearly shown in Figs. 6 and 7, and the invention contem-

plates a simple latch which may be made above the sheet 10 if it is desired to remove in any suitable manner or as shown in Fig. 7. A lug 20¹ may be formed integrally with member 16 at the position on the curled part 5 engaging hinge pin 17 in a manner to present a projection beneath which locking member 20² may be disposed when the bar 16 is in the open position. As clearly illustrated in Fig. 7, member 20² should be carried by strip 14 and slidably mounted thereon by a rivet or like means 20³ which passes through slot 20⁴.

Each of the many overlapping sheets 10 has a plurality of equally spaced punchings 21 to allow the desired amount of offsetting to expose as much of the sheet along one of its edges as is desired. Each sheet 10 should also be cut to form a margin between the punchings 21 and its bound edge, which is 20 just great enough to fit snugly between the hinge 17 and prongs 12. Thus, an abutment is provided along the bound edge of all the sheets which will preclude swinging or wobbling when the leaf 13 is being turned 25 over prongs 12 of the binder. The cooperation of prongs 12 and gripping bar 16 with the properly sized margin formed on the sheets 10 and their punchings, also prevents 30 objectionable movement of the sheets 10 when leaf 13 is not being turned and sheets 10 are simply being utilized as a part of an accounting system or the like.

This comparatively simple structure permits of sheet manipulation which is extremely desirable in a visible index device as may further be seen from the following:

To assemble a number of sheets 10 for use with this invention, the leaf 13 should first be slipped over one group of the prongs 12 40 of the binder 9 to lie in a substantially horizontal position, as shown in Figs. 2 and 3. Sheets 10 are next placed thereon by threading the prongs 12 of the binder through the punchings 21 thereof with an exposed margin 45 along the upper edge of any desired multiple of the spacing of the punchings in the sheets. Sheets 10 all fall to position on top of gripping member 16 and are more or less in a crooked condition. Gripping member 16 is next raised to the dotted position 50 shown in Fig. 3 and the sheets 10 allowed to drop down against reinforcing member 14 and leaf 13. The proper size margin of each sheet 10 which lies between prong 12 and hinge 17 will align the bound edges of the sheets and bring the upper edges thereof into 55 the properly spaced parallel relation. Gripping member 16 is then allowed to snap down on top of the sheets and the same are held 60 in the desired condition.

With special reference at this time to Figs. 4 and 5 and the method of using this structure when it is desired to remove one of the middle sheets, before prongs 12 are snapped 65 to the open position, all of the sheets lying

are swung over to the position shown at 10' and the prongs then opened, as shown in Figs. 4 and 5. The sheet it is desired to remove is then gripped and drawn upwardly 70 along prongs 12 to the position shown in Fig. 4. It will be noticed that gripping member 16 is raised with the sheet until it reaches the position which is here illustrated in full lines of Fig. 5 where the sheet then 75 becomes too weak to hold the gripping member and it automatically snaps back into the position where it is gripping the remaining sheets positioned beneath the sheet being removed. When sheet 10 reaches the position, 80 shown in dotted lines in Fig. 5, it may be slipped off and the prongs closed. Sheets shown at 10' will then be swung over on top of gripping member 16 and the same action taken as previously described to again 85 position them beneath member 16.

With reference, at this time, to the modified form shown in Figs. 8 and 9, it may be desired to construct the leaf 13 in such a way that it has an angle strip 50 along the bound 90 edge which has one of its legs 51 extending upwardly at right angles to leaf 13 in such a way that it abuts the bound edges of sheets 10. This strip 50 and the leaf should be perforated as at 52 to correspond to the 95 prongs 12 of the binder and the punchings 21 of sheets 10. The opposite edge of leaf 13 carries a gripping strip 53 hingedly mounted as at 54 to rigid strip 55 carried by the free end of leaf 13. This gripping strip 53 is also urged to the closed position by 100 springs 56 or other suitable means, and is swung to the position shown in dotted lines in Fig. 9 when it is desired to remove or insert sheets 10.

While the preferred form of the invention shown in Figs. 1 to 7 inclusive provides a means along the bound edge of the sheets 10 to hold them against raising upwardly along prong 12, it may be desired to incorporate 110 this feature as shown in the modified form which will act as a means of holding the free edges of the sheets 10 against swinging movement relative to leaf 13.

It is understood that many modifications 115 may be made in the invention, and while but two specific forms of the invention have been shown and described, it is desired to be limited only by the scope of the appended claims.

What I claim is:

1. In combination with a loose leaf binder having a plurality of sheet-holding members and a plurality of sheets held in overlapped relation thereby, a sheet-supporting leaf 125 having means abutting an edge of the overlapped sheets after they are positioned on said holding members.

2. In combination with a loose leaf binder having a plurality of sheet-holding members 130

- and a plurality of sheets held in overlapped relation thereby, a sheet-supporting leaf having means abutting an edge of the overlapped sheets and means for exerting a yielding pressure against the face of all said sheets after their edges reach the abutted position. 5 means for yieldably maintaining said bar 40 in the closed position, a plurality of aligned openings through said body member along a line spaced inwardly from one edge thereof and a plurality of notches in the free edge of the gripping bar, said openings and 45 notches being in register when the bar is against the body member.
3. In combination with a loose leaf binder having a plurality of sheet-holding members and a plurality of sheets held in overlapped relation thereby, a sheet-supporting leaf also held by said holding members having means abutting one edge of the sheets and means movable into and out of engagement with the face of the sheets whereby the same are precluded from displacement from against said sheet-supporting leaf. 10
4. In combination with a loose leaf binder having a plurality of sheet-holding members and a plurality of sheets held thereby, a sheet-supporting leaf also held by said holding members beneath said sheets having means abutting one edge of the sheets held thereabove. 20
5. In combination with means for holding a plurality of sheets in overlapped relation, a sheet-supporting leaf having means movable into and out of engagement with the face of said overlapped sheets and means abutting one edge of each of said sheets. 25
6. A sheet-supporting leaf of the character described including a sheet-gripping bar hingedly secured along one edge thereof and a plurality of aligned openings spaced inwardly from said edge for the purpose specified. 30
7. A sheet-supporting leaf of the character described comprising a body member, a gripping bar hingedly mounted thereon and
8. An auxiliary leaf for ring-binders comprising a body member, a plurality of ring-engaging openings therein, a gripping bar 50 hingedly mounted on said body along the edge adjacent said openings and notches formed in the free edge of said bar adapted to straddle the rings when in the operative position. 55
9. In combination with a loose leaf binder having a plurality of sheet-holding rings and a plurality of sheets held in overlapped relation thereby, a sheet-supporting leaf also held by said rings having means abutting one edge of the sheets and means movable into and out of engagement with the face of the sheets, said engaging means adapted to release its hold upon any or all of said sheets when they have traveled a predetermined distance along said rings. 60
10. A sheet-supporting leaf of the character described comprising a body member engageable by a plurality of sheet-carrying rings, a gripping bar mounted thereon for movement into and out of engagement with the sheets supported by said rings and means for locking said gripping bar in the open position said bar being confined within said rings when so locked. 70

In testimony whereof I hereunto affix my signature.
RICHARD M. VAN VALKENBURGH.
